United States Patent Office.

WILLIAM B. JONES, OF CINCINNATI, OHIO.

Letters Patent No. 89,776, dated May 4, 1869.

IMPROVED SOFA, LOUNGE, AND TABLE.

The Schedule referred to in these Letters Patent and making part of the same.

To whom it may concern:

Be it known that I, WILLIAM B. JONES, of Cincinnati, Hamilton county, Ohio, have invented a new and useful Article of Furniture; and I hereby declare the following to be a full, clear, and exact description thereof, reference being had to the accompanying drawings, making part of this specification.

The subject of this invention is a new and useful article of furniture, which in one arrangement of its parts forms an elegant sofa, and which, by a few easy changes, can be made to assume, at will, the form of a lounge or a table.

Figure 1 is a perspective view, showing my improvement in the form of a sofa;

Figures 2 and 3 are front elevations of my piece of furniture, as a lounge and table respectively; and

Figure 4 is an end elevation of the sofa and table, and with the back shown in section, the two latter members being represented unshipped.

A' is a rectangular frame for the seat a, and having erected on its rear corners two standards B B', and having attached to its under sides four legs C, and secured to its ends, by but-hinges D D' E E', two folding arms F G.

The buts or shoulders d d' e e' of said hinges being formed out of the wooden portions of the arms, and seat-rail, and serving in the depressed condition of said arms to support the same in the reclined and horizontal positions respectively, suitable for a lounge. (See fig. 2.)

The arms are secured to their upright position by bolts H, which enter the standards B B'.

The two standards B B' have in their upper ends T-shaped bearings b, for correspondingly-headed pivots I, which project from the ends of the back K, which back has T-shaped pockets k for correspondingly-headed pins L, which project from the under side of the table proper M.

N is a bolt or catch to hold the back to its upright position.

The piece of furniture is converted to a table by simply retracting the bolt N, and giving a quarter rotation to the table upon its pivots I, until it reaches the position shown in fig. 3, so as to rest upon the arms F and G.

When used as a lounge, either or both arms may be depressed, as may be desired.

When used permanently as a sofa, the table proper may be unshipped, or, should it be desired to place two such sofas alongside for a double bed, one or both backs may be unshipped. (See fig. 4.)

It will be perceived that the headed pivots I, in addition to their proper functions, serve as stays to prevent the standards H I from spreading.

While describing the preferred form of my invention, I reserve the right to vary the same in non-essential particulars; for example, spring or cupboard-catches may be used in place of the bolts H and N.

A mirror may be panelled in the under side of the table.

The table and back may be in one piece, if desired, and may be used without the depressible arms.

The inner surfaces of the sofa may have any preferred or customary finish, such as upholstering, caning, &c.

This piece of furniture may be given various forms, as taste or circumstances may suggest; for example, the seat-frame may be shortened so as to form a convertible arm and lounging-chair.

I claim herein as new and of my invention—

1. The rear standards B B' on the seat-frame A, and having the open T-formed sockets or bearings b, for the headed pivots I of the back K, which back forms or is provided with a table, M, which, with said back, is capable of being folded down upon the arms in the manner stated.

2. In combination with the elements of the preceding clause, or their equivalents, the but-hinged and depressible arms F G, having the bolts or catches H, as set forth.

3. Making the table proper and the back, or either of them, separable, in the manner and by the means herein designated.

In testimony of which invention, I hereunto set my hand.

WILLIAM B. JONES.
